(57) **CLAIM**

The ornamental design for a part of electric scooter, as shown and described.

DESCRIPTION

FIG. 1 is a top, front and right side perspective view of a part of electric scooter showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the part of electric scooter which form no part of the claimed design.

The oblique shade lines in the drawings represent reflective surfaces.
